UNITED STATES PATENT OFFICE.

HARRY C. BUHOUP, OF CHICAGO, ILLINOIS.

CAR-BOLSTER.

SPECIFICATION forming part of Letters Patent No. 703,379, dated July 1, 1902.

Application filed March 14, 1902. Serial No. 98,219. (No model.)

To all whom it may concern:

Be it known that I, HARRY C. BUHOUP, a citizen of the United States, residing at Chicago, in the county of Cook, State of Illinois, 5 have invented certain new and useful Improvements in Car-Bolsters; and I hereby declare the following to be a full, clear, and exact description of the same, reference being had to the accompanying drawings, in which—

10 Figure 1 is a side elevation, partly in section, of companion truck and body bolsters embodying my invention. Fig. 2 is a bottom plan view of the body-bolster. Fig. 3 is a top plan view of the truck-bolster. Fig. 4 is a vertical central transverse section of both bolsters. Fig. 5 is a side elevation, partly in section, of a modification of the construction shown in Fig. 1 of the drawings; and Fig. 6 is a vertical central transverse section of the modification.

15 Like symbols refer to like parts wherever they occur.

My invention relates to the construction of bolsters for railway-cars, and is especially directed to the connection between the truck and body bolster and may therefore be taken as embracing within its scope both the body and the truck bolster, inasmuch as the construction is of a companion character, the 20 elements of which may be reversely applied at the will of the constructor—that is to say, the parts are interchangeable.

25 In car-bolsters as at present combined the swivel connections between the truck and body bolster are of two characters—viz., center plates and king-bolts or shallow cups and king-bolts—and are located in whole or in part outside the normal lines of the bolsters, while the horizontal forces are applied through the 30 body-bolster, and the resistance acts through the truck-bolster, as a result of which there is a constant tendency of the body-bolster to lift and rock on the truck-bolster, which destroys the extended contact of the bearing-40 surfaces, inducing torsional strains which result from such eccentric application of the forces incident to the draft and load, and, further, the rocking of the bolsters in curving produces like results. Owing to this tendency of the body-bolster to rise, the king-bolt is an essential of all center-plate and shallow-cup constructions, and owing to said

center-plate and shallow-cup constructions and the resultant distance between bolsters the middle depths of the bolsters are limited 55 with proportionate loss of strength or carrying capacity, which is especially noticeable in the body-bolster. While under the present constructions and the maximum depth allowed body-bolsters it is possible to obtain 60 a satisfactory truck-bolster of sufficient carrying capacity, the same cannot be said of body-bolsters.

The object of my present invention is to overcome the hereinbefore-recited objections 65 to the present construction of bolsters and in doing so to obtain a connection between the body and truck bolsters which shall insure uniform and extended support for the parts without interfering with the necessary relative movement of the bolsters and in such manner as to obtain an increased depth on the middle line of the bolster with resulting 70 rigidity of the bolsters under the load; and to this end the main feature of my invention 75 may be generally stated to consist in the combination of a body-bolster and a truck-bolster having a connection comprising counterpart members having spherical bearing-surfaces, said members being of a depth substantially equal to the radius of curvature of the 80 lowest part of said bearing-surfaces, whereby the space between the bolsters may be reduced to the minimum without interfering with the necessary relative movements of the 85 bolsters, uniform and extended support is afforded the parts, lost motion avoided in all positions of the bolsters, whether in draft, buffing, or curving, and the depth of the bolsters (singly and jointly) increased on the center or median line, whereby increased stiffness and load capacity results.

A further feature of my invention consists in compounding spherical surfaces of different radii (or concentric surfaces) whereby the 95 continuous contact of the bearings is preserved and the depth of the engaging members increased, with a corresponding increase in the rigidity and capacity of the individual bolsters and stiffness of the combined bolsters under draft, buffing, and curving forces.

There are other minor features of invention, all as will hereinafter more fully appear.

I will now proceed to describe my invention

more fully, so that others skilled in the art to which it appertains may apply the same.

In the drawings, A indicates a truck-bolster, and B a body-bolster, which so far as 5 their general construction is concerned may be of any approved form and so far as material is concerned may be of any suitable material—as, for instance, angle-iron, T-iron, plates, or pressed steel—but is preferably 10 cast-steel for reasons which will hereinafter appear. The central connection of said bolsters I form of counterpart sections, one of which, the entering or included element 1, is of a projection having spherical bearing-sur- 15 faces, or, in other words a figure bounded by the curved surfaces 1^a 1^a, which if continued, as indicated in dotted lines, Fig. 1, and in full lines, Fig. 5, would result in a hemisphere, and with a radial projection or 20 cylindrical extension 2, which preferably terminates in the curved face 1^b, the curved surfaces 1^a 1^a and 1^b being concentric or substantially concentric and which taken together are the equivalent of a hemisphere. 25 Said entering or included element may be directly connected to or formed on or with either the body-bolster or truck-bolster, but is preferably formed on or connected with the body-bolster as a means of increasing the cen- 30 tral depth and strengthening said bolster.

3 indicates the including or receiving member of the connection, which is likewise formed with its curved interior surfaces 3^a 3^a, corresponding with the curved outer faces 35 1^a 1^a of the included member 1, and with a cylindrical extension or pocket 4 to receive the cylindrical extension 2, but of sufficiently greater diameter to permit of the vibration of the included extension 2, said extension 40 being closed by a spherical bottom 3^b, concentric with the spherical side walls 3^a 3^a and perforated, as at 5, to permit of the escape of dust or dirt. The including member 3 of the connection is preferably located on the 45 truck-bolster and has its lines substantially or entirely within the normal lines of the bolster to minimize the distance or space between the bolsters.

As indicated in the drawings, the included 50 element preferably has a bearing on the bottom (or closed end 3^b) of the including element, and this is of value where the included element is applied to the body-bolster, as the load is thereby lowered to a point between 55 the points of support of the truck-bolster; but said extension 2 need not of necessity have a bearing on the bottom of the including element, especially if the including element 3 is on the body-bolster, and in the 60 latter case the clearance-hole 5 may also be dispensed with.

Owing to the form and depth of the bolster connections above described the same are 65 preferably produced by casting, and, as before noted, may be inserted in and connected with the other members of the bolsters according to their character and manner of

construction, whether angle-iron, plate, T, or I beams; but by preference I cast the bolsters and central connections integral, in 70 which case the bolsters may each comprise the side pieces a a, either with or without flanges, and end pieces b b, either with or without bottom and top plates for the body and truck bolsters, and a series of intermediate 75 strengthening ribs or webs] 6, disposed about the central connection as circumstances may dictate.

At the proper points on opposite sides of the center and on the opposing faces of the 80 bolsters are cast or otherwise formed on the truck-bolsters ball-cups 7, and on the body-bolsters arc-shaped lugs or projections 8, whose cross-section has to the inner side of its flat face a curved dependent flange substantially equal to one-fourth of a circle and 85 constituting a race-way for the ball 9, the whole constituting a side bearing substantially integral with the bolster when cast.

Owing to the peculiar construction of the 90 center bearing, whereby all lost motion is eliminated, and the particular form of the quarter-circle raceway, the ball 9 will be given a constant spinning motion during the movement of the bolster when not otherwise rotated by the top plate. 95

Having thus described my invention, what I claim, and desire to secure by Letters Patent, is—

1. The combination of a body-bolster and a 100 truck-bolster having a central connection comprising counterpart members fixed with relation to the respective bolsters, said members having spherical bearing-surfaces, the entering member having a depth substantially equal to the radius of curvature of the lowest part of said bearing-surfaces, substantially 105 as and for the purposes specified.

2. The combination of a body-bolster and a 110 truck-bolster having a central connection comprising counterpart members the bearing-surfaces of which are composed of segments of concentric hemispheres, substantially as and for the purposes specified.

3. The combination of a body-bolster and a 115 truck-bolster having a central connection comprising members having corresponding concentric bearing-surfaces, the included member having an extension which intersects the including member, substantially as and 120 for the purposes specified.

4. A cast-metal bolster having a centrally-disposed projection provided with spherical bearing-surfaces, said central projection having a depth substantially equal to the radius 125 of curvature of the lowest part of said bearing-surfaces, substantially as and for the purposes specified.

5. A cast-metal bolster having a centrally-disposed bearing projection compounded of 130 concentric spherical surfaces of depth substantially equal to the radius of curvature of the greater sphere, as and for the purposes specified.

6. A cast-metal bolster having a centrally-disposed spherical bearing projection and a radial extension therefrom substantially as and for the purposes specified.

5 7. A cast-metal bolster having parallel sides, interposed webs, and a centrally-disposed projection provided with spherical bearing-surfaces the depth of said projection being substantially equal to the radius of
10 curvature of the lowest part of said bearing-

surfaces, substantially as and for the purposes specified.

In testimony whereof I affix my signature, in presence of two witnesses, this 14th day of March, 1902.

HARRY C. BUHOUP.
